Primary Examiner — Robin V Webster*Assistant Examiner* — Rachel A Voorhies(74) *Attorney, Agent, or Firm* — McDonald Hopkins LLC(57) **CLAIM**

The ornamental design for a winch housing, as shown and described.

DESCRIPTION

FIG. 1 is a front left perspective view of a winch housing showing our new design;

FIG. 2 is a front plan view thereof;

FIG. 3 is a rear plan view thereof;

FIG. 4 is a right side plan view thereof;

FIG. 5 is a left side plan view thereof;

FIG. 6 is a top plan view thereof; and,

FIG. 7 is a bottom plan view thereof.

The features shown in broken lines in the drawing figures depict environmental subject matter only and form no part of the claimed design.
